HENRY M. KEITH

INTRODUCTION

INVENTOR

WITNESS: Lee Smith

UNITED STATES PATENT OFFICE

HENRY M. KEITH, OF HARRISBURG, ILLINOIS, ASSIGNOR TO THE GASKINS-KEITH COMPANY OF ILLINOIS, A CORPORATION

FRESH WATER SYSTEM

Application filed August 20, 1930. Serial No. 476,589.

This invention relates to new and useful improvements in water systems especially adaptable for use with wells to furnish water therefrom to dwellings and the like and has for the primary object, the provision of a device of the above stated character whereby air pressure may be employed to force the water from a well through a system to a dwelling or building and permit the water to be dispensed or used in the customary manner consequently obviating the necessity of pumping the water from the well and manually carrying the water to the dwelling for use.

Another object of this invention is the provision of a chamber located in and receiving water from the well and connected to the water system of a dwelling and to an air pressure source that the water therein may be forced through the system and used as desired.

A further object of this invention is the provision of an automatic valve to control the air pressure to the chamber as the water is dispensed from the system and which will automatically vent or place the chamber under atmospheric pressure when the dispensing of the water from the system is discontinued to permit the chamber to replenish itself with water from the well.

A still further object of this invention is the provision of a water system of the above stated character which will be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a vertical sectional view illustrating a water system constructed in accordance with my invention and applied to a well and to a dwelling adjacent thereto.

Figure 2 is a vertical sectional view illustrating a chamber to be located in the well.

Figure 3 is a side elevation partly in section illustrating an automatic control valve for the system.

Figure 4 is a similar view illustrating the valve positioned to permit the air pressure to reach the chamber for forcing the water therefrom into the system.

Referring in detail to the drawings, the numeral 1 indicates a well having a building or dwelling 2 located adjacent thereto and to which my invention is applied.

A chamber 3 is suitably supported in the well 1 and submerged in the water as clearly shown in Figure 1 and has in the bottom wall thereof a foot valve 4 for the purpose of admitting water from the well into the chamber 3. The foot valve 4 is of the check type which will permit water to flow into the chamber but will prevent the water from passing out of the chamber when force is applied thereto. A suitable strainer 5 is positioned on the foot valve for the purpose of preventing foreign matter from entering the well. An outlet pipe 6 extends to a point adjacent the bottom wall of the chamber 3 and is provided with a check valve 7 and extends through the top wall of the chamber 3 and outwardly through the side of the well as shown in Figure 1 and thence into the basement of the dwelling and upwardly to a desired room where the same has a control valve or faucet 8 applied. The valve 8 is associated with a sink or basin 9 provided with the usual drain pipe 10.

An automatic control valve 11 is connected to the pipe 6 preferably within the basement of the building or dwelling and has connected thereto air pipes 12 and 13 and the pipe 13 is in turn connected to an air pressure source 14 located in the basement and in the form of a tank having an air pressure gauge 15. A suitable compressor 16 is connected to the tank 14 for the purpose of building up air pressure therein and may be driven in any suitable manner such as by a gasoline engine or an electric motor when electricity is available. The power source for the compressor 15 may be of an automatic nature so that the

- air pressure within the tank 14 will be maintained to a desired pressure at all times. The pipe 12 extends from the basement into the well and through the top wall of the chamber 3 for the purpose of placing the interior of the chamber 3 under air pressure from the source 14. The air pressure in the chamber 3 will expel the water from the chamber through the pipe 6 which constitutes the water system to the building or dwelling and the water may be dispensed by opening the faucet or valve 8.

The control valve 11 includes a pressure chamber 17 having a pipe 18 which is connected to the pipe 6 by a T-coupling 19. The upper end of the pressure chamber 17 is threaded into a casing 20 which includes a compartment 21 and air compartments 22 and 23. The compartment 22 has the pipe 13 connected thereto while the compartment 23 has the pipe 12 connected thereto. The compartments 22 and 23 are separated by an apertured partition 24 having a valve seat about the aperture thereof to be engaged by a ball valve 25 supported by a coil spring 26 mounted on an adjustable plate 27 located within the compartment 22. The plate 27 is adjustably secured to the bottom wall of the compartment 22 by a stud bolt 28 whereby the tension of the spring on the ball valve 25 may be varied as desired.

A vent pipe 29 open to the atmosphere is slidably mounted in the top wall of the compartment 23 and is of a size that the same may pass through the aperture of the partition 24 to be engaged by the ball valve 25 when the valve is in the position as shown in Figure 4 for the purpose of closing the chamber 3 to the atmospheric pressure. It is to be understood that when the vent tube 29 is positioned as shown in Figure 3 the chamber 3 is in direct communication with the atmosphere through the pipe 12 so that water from the well may fill the chamber 3.

The compartment 21 is known as the diaphragm compartment and has located therein a diaphragm 30 that overlies the open upper end of the pressure chamber 17 of the valve and has connected thereto a rod 31 by a head 32 and the rod extends through the top wall of the compartment 21 and has adjustably secured to its upper end an arm 33 which is in turn adjustably secured to the vent pipe 29 for the purpose of moving the vent pipe according to the position of the diaphragm. A coil spring 34 is positioned between the top wall of the compartment 21 and the head 32 for the purpose of urging the diaphragm into a position as shown in Figure 4 for the purpose of positioning the vent tube and ball valve 25 so that air pressure from the source 14 can pass into the chamber 3 to expel water from the chamber through the pipe system when the control valve 8 is open. When the valve 8 is closed,

the pressure of the water in the pipe 6 and the chamber 17 of the valve raises the diaphragm into a position as shown in Figure 3 which elevates the vent tube 29 and allows the ball valve 25 to engage the seat in the partition 24 stopping the flow of air pressure from the source 14 into the compartment 23 and consequently to the chamber 3 located in the well. With the vent tube 29 thus positioned, the lower end thereof is disengaged from the ball and the chamber 3 in the well is placed under atmospheric pressure through the pipe 12 permitting the water in the well to fill the chamber 3. When the valve 8 is again opened, the pressure in the water system is reduced, consequently reducing the pressure in the chamber 17 of the valve and the diaphragm is moved downwardly into the position shown in Figure 4 by the influence of the spring 34 consequently again placing the chamber 3 under air pressure from the source 14 which air pressure will expel the water therefrom through the pipe 6 to the valve 8.

While I have shown and described the preferred embodiment of my invention, it will be understood that minor changes in construction, combination and arrangement of parts may be made without departing from the spirit and scope of the invention as claimed.

Having thus described my invention, what I claim is:

1. A valve for a water system comprising a pressure chamber, a diaphragm chamber in communication with said pressure chamber, a diaphragm closing the diaphragm chamber from the pressure chamber, a tension means for urging the diaphragm in one direction, a casing carried by the diaphragm chamber and having a pair of compartments, a valve seat between said compartments, an inlet pipe connected to one of the compartments and to an air pressure source, and outlet pipe connected to the other compartment, a vent tube slidable through the compartments, a spring pressed ball valve in one of the compartments to engage the seat when the vent tube is in one position and to engage the end of the vent tube when the latter is in another position, and an arm adjustably secured to the vent tube and to the diaphragm.

2. A valve for a water system comprising a compressor chamber, a diaphragm compartment carried by said chamber, a valve casing carried by said compartment and having a pair of compartments, a valve seat dividing the last named compartments, a spring actuated ball valve for engagement with the seat, a diaphragm in the diaphragm compartment, tension means for urging the diaphragm in one direction, an arm connected to the diaphragm, and a vent tube carried by the arm and movable through the com-

parts of the casing to be engaged and disengaged by the ball valve.

3. A valve for a water system comprising an air pressure chamber, a diaphragm chamber in communication with the pressure chamber, a diaphragm closing the communication between said chambers, a stem on the diaphragm, a valve casing carried by the diaphragm chamber and having a pair of compartments, a valve seat between said compartments, an arm adjustably secured to the stem, a spring pressed ball valve located in one of the compartments to engage the seat, a vent tube adjustably secured to the arm and movable through said compartments and when in one position adapted to engage the ball valve, and the tension means for urging the diaphragm in one direction.

In testimony whereof I affix my signature.

HENRY M. KEITH.
